UNITED STATES PATENT OFFICE

DAVID HINDAHL, OF CHICAGO, ILLINOIS, ASSIGNOR TO RODGER BALLAST CAR COMPANY, OF CHICAGO, ILLINOIS, A CORPORATION OF MAINE

DUMP CAR

Application filed June 6, 1930. Serial No. 459,442.

This invention relates to an improved construction for ballast cars and has reference more particularly to a dump car, adapted for carrying materials and for discharging the same either between the rails or outside the rails.

In railroad ballast work there is a great advantage in dumping the ballast material at the proper point with respect to the rails in a manner to prevent covering the latter. This results from the fact that in service the car is moved along the track and simultaneously deposits the ballast between the rails and if the material was allowed to flood the rails, derailing of the car and other serious damage would result. In the specific embodiment herein disclosed this is accomplished by employing pivotally mounted extensions forming a continuation of the inner 15 hopper side walls and which are caused to swing open as the hopper doors open but which remain in contact with the doors sufficiently to prevent discharge of the material until the free edge of the door has been lowered to a predetermined point. It is also commercially desirable at times to employ the type of car described for transporting coal and for this purpose the feature set out above is not important but it is necessary to have a 20 discharge opening for the coal of maximum size.

It is therefore one of the primary objects of the present invention to provide a dump car embodying novel features of construction whereby the same will be equally efficient in properly depositing ballast material with respect to the rails and also in discharging coal and the like.

A yet further object of the invention is to provide a dump car in which the center sill structure of the car is provided with means cooperating with the free edge of the downwardly swinging hopper doors in such a manner as to prevent the discharge of material from the hoppers until the doors have reached a predetermined point.

Another object of the present invention is to provide a dump car having hopper doors which will properly deposit the ballast material along the center of the roadbed and

which will also embody novel features for increasing the size of the opening between the lower portion of the hopper doors and the central shedding surfaces of the car.

With these and various other objects in view, the invention may consist of certain novel features of construction and operation, as will be more fully described and particularly pointed out in the specification, drawings and claims appended hereto.

In the drawings, which illustrate an embodiment of the device and wherein like reference characters are used to designate like parts—

Figure 1 is a transverse sectional view of a dump car embodying the construction of the present invention; and

Figure 2 is a transverse sectional view of a dump car similar to Figure 1 but showing the dumping mechanism in discharged position.

The present invention is shown as applied to a railway ballast car having the usual side walls 10, end walls 11 and bottom, which in this case is a hopper bottom, comprising two hoppers 12 formed on opposite sides of a longitudinally extending center sill structure. The sill structure includes a plurality of spaced vertical beams 13 having disposed over them a longitudinally extending member 14 provided with inclined side surfaces 15 and secured to the ends of the car by flanges 16. Also secured to each end structure of the car and extending longitudinally thereof are members 17 which are inclined and serve to join the side walls 10 with the hopper doors, to be presently described. These members form shedding surfaces and serve to direct the ballast material towards the hopper openings 12 as does also the member 14 by reason of the 90 shedding surfaces 15, described.

It is of course understood that the center sill members comprising the beams 13 form the inner walls of the longitudinally extending hoppers 12 and for this reason are provided with members 18 which extend downwardly and outwardly from beams 13 to form a continuation of the inner hopper side walls. The members 18 are pivotally secured to the lower flanges of the beams 13 as at 20 by 100

means of brackets 21 secured to the lower flanges by any suitable means. It is therefore seen that the members 18 not only form a continuation of the inner walls of the hopper but also function as pivoted doors and when in closed position have engagement with the main hopper doors, to be described, to form a portion of the hopper bottom.

The other or outer walls of the hoppers 12 are formed by door structures in each case including a door frame 22 pivotally connected at its upper edge as at 23 to the car structure by means of any suitable bracket or support 24. The door frame in each case extends considerably beyond the lower extremity of its associated hopper wall 18 when in closed position as shown in Figure 1.

Pivottally mounted in each of these door frames are one or more doors 25, which preferably are pivoted in the door frames as at 26 at a point just below the lower extremity of the associated inner hopper side wall 18, so that when the doors 25 are in open position the surface of the doors 25 and the members 18 will form a continuous shedding surface which may or may not be in the same plane in accordance with requirements. The opening and closing movements of the doors 25 are controlled by any suitable door operating mechanism, including chains 27 operatively connected to the doors and to operating shafts 28 journaled in the brackets 24.

Particular reference will now be had to the means whereby the flow of dumpable material from hoppers 12 may be accurately controlled and more specifically to means whereby ballast material is properly deposited with respect to the rails and prevented from covering the latter. This comprises the operating mechanism for controlling the opening and closing movements of the door frames 22 which mechanism consists of an operating shaft 30, preferably square in cross-section and journaled in U-shaped brackets 31, which brackets are secured to and depend from the lower flanges of the vertical beams 13. Located on the shaft 30 are a plurality of crank arms 32, each arm having pivotally secured to its lower end a link 33 of the formation as shown in Figure 2. To the free end of the links 33 is pivotally secured hanger arms 34 which arms are in turn pivotally secured at 35 to the lowermost end of the door frames 22. For controlling opening and closing of the frames 22 therefore, it is only necessary to rotate the operating shaft 30 which will in turn impart the necessary rotation to the crank arms 32 which serves to lift the hanger arms 34 and locate the same over the operating shaft 30, as shown in Figure 1, so that with the door frames 22 in closed position the entire weight of the ballast material upon the doors will be supported from the brackets 31 and thus from

the center sill structure including the beams 13.

A feature of the present invention in connection with this opening and closing of the frames 22 so as to deposit the ballast material substantially centrally of the roadbed, comprises operating mechanism for simultaneously imparting rotation to the members 18 so as to cause more efficient dumping of the material. This mechanism comprises a plurality of levers 38, each lever pivotally secured at 39 to the lower end of the door frame 22 at a point somewhat removed from the pivot 35 of the arms 34. Each lever 38 is also pivotally secured at its other end to the member 18 located opposite to its particular door frame 22 to which the lever is secured. Each lever 38 therefore is disposed diagonally to its companion lever and functions to impart the necessary rotation to the members 18 about their pivot point 20 as the various door frames 22 are opened or closed according to the operation of the operating shaft 30. By reference to Figure 2, it is seen that this construction of pivotally securing the levers at one end to the frames 22 and at their other end to a member 18, will function to impart counterclockwise rotation to one of the members, and clockwise rotation to the other member. This movement of the members 18 takes place immediately upon the lowering of the door frames and increases in the rapidity of its movement as the opening of the door frames 22 continue.

When it is desired to deposit lading between the rails 8-8 the operation is accomplished by lowering of the door frames 22. It is to be noted that when the frames are in closed position the members 18 have contacting engagement with and form with the frames or more correctly with the doors 25 an angle which is greater than a right angle. Upon a lowering of the frames the members 18 are caused to pivotally rotate as described which movement is such that contact between the frames 22 and the members 18 continues until the angle between them assumes a right angle. This position of the parts is clearly shown in dotted lines in Figure 2. It is thus seen that discharge of the material is prevented until the frames are lowered to a predetermined point. This feature is particularly important in the construction of ballast cars.

The structure described also allows more efficient dumping of the material by materially increasing the size of the discharge opening. In previous constructions the size of the discharge opening was defined by the lower end of the inner hopper walls and the door frames when the same were in discharge position. However, in the present construction the inner hopper walls, which in this case include the members 18, are simultaneously

given a rotation in a direction so that the opening through which the material is discharged is considerably increased. The present invention therefore results in a dump car 5 which will embody structure for adapting the same for use as a coal car without sacrificing any of the features desirable in ballast car construction.

Another feature of the invention resides in 10 the fact that although the members 18 have pivotal movement simultaneously with the opening and closing of the frames 22, they also form a portion of the hopper bottom when the frames are in closed position since 15 the members 18 are then disposed in sloping position with respect to the frames and have engagement against the doors 25 so as to complete the hopper bottom.

It is to be understood that I do not wish 20 to be limited by the exact embodiment of the device shown, which is merely by way of illustration and not limitation, as various and other forms of the device will of course be apparent to those skilled in the art without 25 departing from the spirit of the invention or the scope of the claims.

I claim:

1. In a hopper car, a hopper and means for 30 closing said hopper, including a door comprising a part of the hopper bottom and a member cooperating with said door at a point intermediate its length to complete the hopper bottom, said member having movement during the opening of said door to materially increase the size of the discharge opening.

2. In a hopper car, a hopper and means for 35 closing said hopper, including a door comprising a part of the hopper bottom and a member cooperating with said door to complete the hopper bottom, said member forming 40 an extension of the inner hopper wall and engaging the door when closed intermediate its length, and means imparting rotation to said member during the opening of 45 said door to increase the size of the discharge opening.

3. In a hopper car, a plurality of hoppers, 50 doors for closing said hoppers, said doors being pivotally mounted with their free edges extending towards each other, members comprising inner hopper walls and engaging said doors intermediate its length when in closed 55 position to complete the hopper bottom, said members being adapted for movement during the opening of the doors to increase the discharge opening.

4. A car of the class described having a 60 bottom comprising a longitudinally extending hopper, said hopper having an inner wall and an outer movable wall, said inner wall including a pivotally mounted extension having engagement with said movable wall at a point intermediate its length when in closed 65 position, and means for imparting rotation

to said extension during the opening movements of said movable wall.

5. A car of the class described having a bottom comprising a longitudinally extending hopper, said hopper including a door structure pivotally mounted at its upper end and movable to control the flow of dumpable material to a point between the rails, and means actuated by said door during movement thereof for facilitating the flow of said 70 dumpable material.

6. A car of the class described having a center sill forming wall portions of oppositely arranged hoppers, said center sill including longitudinally extending beams and 80 having members pivotally secured thereto forming extensions of said wall portions, pivotally mounted doors forming the other wall of said hoppers, said doors and said pivotally secured members being movable simultaneously 85 to facilitate discharge of material from said hoppers.

7. A car of the class described having a center sill forming wall portions of oppositely arranged hoppers, said center sill including longitudinally extending beams, members pivotally secured to said beams and forming extensions of said wall portions, pivotally mounted doors forming the other wall of said hoppers, and means connecting 90 the free ends of said members with the free ends of said oppositely located doors, whereby said members are rotated during the opening movements of said doors in a direction to increase the size of the discharge openings. 95

8. A car of the class described having a center sill forming inner wall portions of oppositely arranged V-shaped hoppers, said center sill including longitudinally extending beams, members pivotally secured to said 100 beams and forming extensions of said inner wall portions, pivotally mounted doors forming the outer wall of said hoppers and cooperating with said members when in closed position to form the bottom of said hoppers, levers pivotally secured to the free ends of 105 said doors and having pivotal connection to oppositely located members, and means for imparting opening and closing movements to said doors, the opening movement of said doors imparting rotation to said members in a direction to increase the size of the discharge opening.

9. A car of the class described having a center sill, a hopper, an inclined swinging door normally closing said hopper, said door having a free edge extending toward the center sill, and pivotally mounted means cooperating with the door at a point intermediate its length to prevent discharge of material from the door until its opening movement has reached a predetermined point. 120

10. A car of the class described having a center sill, a hopper, an inclined swinging door normally closing said hopper, said door 125

having a free edge extending toward the center sill, pivotally mounted means depending from said center sill, said means cooperating with the door at a point intermediate its length to prevent discharge of material from the door until its opening movement has reached a predetermined point.

11. A car having a bottom comprising a longitudinally extending hopper, one side of said hopper including a pivoted extension, the other side of said hopper including an inclined door normally engaging the pivoted extension and mounted to swing away from said extension to discharge the load to one side of the rail, or to swing into line with said extension to discharge the load to the other side of the rail.

12. A car of the class described having a center sill, a bottom comprising a substantially V-shaped hopper having a downwardly extending extension forming the inner side and being pivotally secured to said center sill, a downwardly and inwardly inclined outer side, the inner end of said outer side extending beyond the lower edge of the pivoted extension, and means for discharging the load through said hopper toward the center or toward the side of the car.

Signed at Chicago, Illinois, this 29th day
of May, 1930.

DAVID HINDAHL.
